UNITED STATES PATENT OFFICE.

GEORGE F. WOOD-SMITH, OF PITTSBURGH, PENNSYLVANIA.

END ANCHORAGE FOR TANK-CARS.

1,245,850.

Specification of Letters Patent.

Patented Nov. 6, 1917.

Application filed May 25, 1917. Serial No. 170,843.

To all whom it may concern:

Be it known that I, GEORGE F. WOOD-SMITH, a citizen of the United States, residing in the city of Pittsburgh, county of 5 Allegheny, State of Pennsylvania, have invented a new and useful End Anchorage for Tank-Cars, of which the following is a specification.

My present invention consists of a novel 10 construction of an end anchorage for tank cars wherein provision is made for taking up the wear of the wooden head block, or the contraction of the tank, or to overcome defective workmanship in fitting the head 15 block to the curvature of the tank.

It further consists of a novel construction 20 of an adjustable end anchorage in which a buffer and chafing casting is employed for tying the center sill channels together, and which also acts as a buffer for the coupler to strike against and as an abutment for the head block bracing member with which the wedges coöperate to 25 compensate for the longitudinal movement of the tank.

It further consists of novel means for locking the wedges in their adjusted position, and also novel means for eliminating in a large measure the shearing strain on 30 the rivets and changing the shearing strain to a tension strain.

It further consists of a novel construction 35 of a buffer, a novel construction of brace members, a novel construction of wedges, a novel construction of a channel, a novel arrangement of such parts, and other novel features of construction, all as will herein-after more fully appear in the detailed description of my invention.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a plan view of an end anchorage for tank cars embodying my invention.

Fig. 2 represents a side elevation of Fig. 1.

Fig. 3 represents a bottom plan view of the buffer and chafing casting.

Fig. 4 represents an end elevation of Fig. 1.

Fig. 5 represents a plan view of one of 60 the wedges.

Fig. 6 represents a side elevation of Fig. 5.

Fig. 7 represents a transverse section of Fig. 5.

Fig. 8 represents a side elevation of the 65 buffer and chafing casting seen in Fig. 3.

Similar numerals of reference indicate corresponding parts in the figures.

Referring to the drawings.

1 and 2 designate the center sills which 70 carry the bolster 3. 4 designates the tank which is supported in any desired manner. 5 designates the wooden head block which is recessed as indicated at 6, in order to conform to the movement of the end of the tank, 75 said head block being mounted on plates or bars 7, carried by the center sills, such bars terminating at 8 and said head block being angularly recessed as is indicated at 9.

10 designates a channel beam which abuts 80 against the wooden head block 5. 11 are stay rods passing through the head block and the channel 10, as will be understood by reference to Fig. 1, and provided with nuts 12, and turn buckles 13 which also engage in the usual manner the rods 14, the outer ends of which are flattened as indicated at 15 in order that they may be secured to the bolster 3 by means of fastening devices 16 of any desired type. 90

17 designates a buffer and chafing casting which is provided with a striking plate 18 which is preferably curved as indicated at 19, in Fig. 3, and is provided with a flange 20 apertured as indicated at 21 in order to receive the fastening devices 22. The casting 17 is provided with an upwardly extending lip 23 which extends above the laterally extending top face 24, the forward end of which is offset as indicated at 25 in order 100 that the same may be seated on the end of the plate or bar 7 and support the channel 10, it being understood that two of the offset portions 25 are provided and that the same are fastened to the center sills by 105 means of rivets or equivalent fastening devices 26, which also pass through the plate 7. The laterally extending portions 24 of the buffer casting 17 are adapted to support the head block brace or casting 27, the rear 110

face 28 of which is adapted to abut against the lip 23 while the forward face thereof is inclined as indicated at 29, and provided with an angular shaped recess 30, the walls 5 of which are also inclined, thereby adapting the same to receive the bottom flange 31 which runs along the length of the wedge 32, it being best understood by reference to Figs. 1 and 5 that the outer face of the flange 31 is inclined as indicated at 33, and the latter being adapted to coact with the inclined face 29 of the head block casting 27. The inner face of the wedge 32 is preferably cored out as indicated at 35, thereby forming the rectilinear face 36 which engages with the inner face 37 of the channel 10. The top and bottom faces of the wedge 32 which are preferably inclined as seen at 38 and 39 respectively, in Fig. 7, it being understood that the face 39 is adapted 20 to travel on the lower flange of the channel 10.

Each wedge 32 is provided with a boss or lug 40 having a desired number of apertures 41 therethrough, it being apparent from Fig. 1 that the channel 10 is provided with apertures 42, through which are adapted to pass fastening devices 43. In practice the apertures in the wedges and channel are placed at different distances apart in order 30 to provide means for locking the wedges in their adjusted position after slight adjustment of the wedges.

The head block casting 27 is secured in 35 position with respect to the center sills by the rivets 44, which also serve as means for securing the buffer casting 17 to the center sills. The rivets 45 on the inside of the head block casting 27 do not pass through the center sills 1, but simply pass through the head block casting 27 and the buffer casting 17, as will be understood by reference to Fig. 1. The buffer casting 17 is also provided with a reinforcing flange 46 in 40 order that the center sills 1 and 2 may fit therein, as will be understood by reference to Figs. 2 and 3.

It will now be apparent that in case 50 there is wear between the head block and the tank, or contraction has taken place in the wooden head block, or if the head block has not been properly fitted to the curvature of the tank, the wedges 32 are driven in and in order to prevent them slackening 55 off, due to vibrations in transit, the fastening devices such as pins 43 are placed through the apertures 42 and the apertures 41 registering therewith.

Special attention is directed to the novel 60 construction and coöperation of these wedges and also the manner in which the flange 31 prevents the lifting or rising of the wedges.

Special attention is also directed to the 65 lip 23 which takes a part of the shearing strain off the rivets and also changes the

shearing strain on the rivets to a tension strain.

The turn buckles 13 may be adjusted as desired, in order to take up any slack in the tie rods 11 and 14.

It will now be apparent that I have devised a novel and useful construction of an end anchorage for tank cars, which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent is:—

1. In a tank car, center sills, a buffer secured thereto having a lip, a head block brace engaging said lip, a head block, a tank, and an adjustable wedge intermediately of said head block brace and tank.

2. In a tank car, center sills, a buffer secured to the center sills and having a striking plate, a head block, brace abutting against and supported on said buffer, a tank, a head block, wedges between the head block and the head block braces, and means for preventing rearward movement of the wedges.

3. In a tank car, center sills, a buffer secured thereto having a lip, head block braces abutting against said lip and secured to said buffer, a tank, a head block, a channel, and wedges between said head block braces and said channel.

4. In a tank car, center sills, a buffer secured thereto having a lip, head block braces abutting against said lip and secured to said buffer, a tank, a head block, a channel, wedges between said head block braces and said channel, and means for interlocking said wedges with said channel.

5. In a tank car, center sills, a buffer secured thereto having a lip, head block braces abutting against said lip and secured to said buffer, a tank, a head block, a channel, wedges between said head block braces and said channel, means for interlocking said wedges with said channel, and adjustable connections between said bolster and channel.

6. In a tank car, center sills, a buffer secured thereto, a head block brace secured to said center sills and said buffer, a wedge engaging said buffer and having a flange coacting therewith to prevent upward movement of said wedge, a tank, and a head block intermediately of said wedge and tank.

7. In a tank car, center sills, a buffer se-

cured thereto, a head block brace riveted to said buffer and center sills, said buffer having means coacting with said head block brace to eliminate the shearing strain on the rivets, a tank, a head block, and means intermediate said head block brace and head block for maintaining said head block in proper relation with respect to said tank.

8. In a tank car, center sills, a buffer secured thereto and means forming an abutment, a head block brace riveted to said buffer and center sills and engaging said means to prevent shearing strain on the rivets, a tank, a head block engaging the end of the tank, a channel supported on the buffer and abutting against the head block, and a wedge intermediate the head block brace

and said channel to adjust said head block with respect to said tank.

9. In a tank car, center sills, a buffer secured thereto, and having means forming an abutment, a head block brace riveted to said buffer and engaging said abutment, the forward face of said head block brace being inclined, a wedge coacting with the inclined face of the head block brace, a tank, a head block intermediate of the tank and said wedge, and means for locking said wedge in its adjusted position.

GEORGE F. WOOD-SMITH.
